CLAIM

The ornamental design for a truck bed mattress as shown and described.

DESCRIPTION

FIG. 1 is a perspective view of a truck bed mattress according to the present invention.

FIG. 2 is a front view of the invention shown in FIG. 1.

FIG. 3 is a rear view of the invention shown in FIG. 1.

FIG. 4 is a side view of the invention shown in FIG. 1.

FIG. 5 is a second side view of the invention shown in FIG. 1.

FIG. 6 is a top view of the invention shown in FIG. 1; and, FIG. 7 is another perspective view thereof, showing the truck bed mattress as used in a vehicle.

The broken lines shown in FIGS. 1-7 illustrate portions of the truck bed mattress that form no part of the claimed design. The broken lines shown in FIG. 7 depict the environment of a vehicle which forms no part of the claimed design.
